UNITED STATES PATENT OFFICE

169,772

FINGER ASH TRAY

Snowden B. Lonberger, Washington, D. C.

Application February 3, 1953, Serial No. 23,417

Term of patent 14 years

(Cl. D85—2)

To all whom it may concern:

Be it known that I, Snowden B. Lonberger, a citizen of the United States, residing at Washington, in the District of Columbia, have invented a new, original, and ornamental Design for a Finger Ash Tray, of which the following is a specification, reference being had to the accompanying drawing, forming part thereof.

Fig. 1 is a perspective view of a finger ash tray, showing my new design;

Fig. 2 is a perspective view thereof, showing the side opposite that shown in Fig. 1;

Fig. 3 is a rear elevational view thereof;

Fig. 4 is a side elevational thereof;

Fig. 5 is a top plan view thereof; and
Fig. 6 is a bottom plan view thereof.

I claim:

The ornamental design for a finger ash tray, as shown.

SNOWDEN B. LONBERGER.
